By his Attorney *W. A. Oldenmuller*

UNITED STATES PATENT OFFICE.

OTTO LÖWENBERG, OF COLOGNE, GERMANY.

CABLE-LUBRICATOR.

1,160,919.

Specification of Letters Patent. Patented Nov. 16, 1915.

Application filed April 25, 1913. Serial No. 763,567.

To all whom it may concern:

Be it known that I, OTTO LÖWENBERG, subject of the German Emperor, residing at Cologne, Germany, have invented new and useful Improvements in Cable-Lubricators; and I do hereby declare the following to be a full, clear, and exact description of the same.

This invention relates to a lubricating device for the carrying cables of cable railways, in which a forcing pump is arranged at the bottom in the oil tank and forces the oil to a point above the carrying cable. Lubricating devices of this kind are already well known, but the present invention is a great simplification compared to the well known devices, as regards the transmission of movement from the running gear to the pump. The movement is transmitted by a straight spindle which is carried through the suspension journals of the car suspension. The spindle is rotated by means of a bevel wheel gear which is arranged in such manner that the axle of the driving wheel coincides with the suspension journal, so that in case of oscillations of the suspension relatively to the running gear, the proper engagement of the bevel wheel pair is not disturbed.

30 A construction according to this invention is illustrated by way of example in the accompanying drawing in which—

Figure 1 shows the running gear with a portion of the suspension in side elevation; Fig. 2 is a section in the center through the running gear and Fig. 3 shows the bottom portion of the suspension with the oil tank. Fig. 4 is a side elevation of the suspension as a whole.

40 The running gear consists of the running gear frame 1 and the running rollers 2 and 3 mounted in the same. Between these two rollers in the frame, 1, is mounted a bolt 4 on the laterally projecting portion of which rests the suspension 5. On the suspension is mounted a box 7 formed into an oil tank and containing the rotary pump 8. The pump in question is driven by the spindle 9, passing centrally through the bolt 4 and carrying at the upper end a bevel wheel 10. The latter is in engagement with a bevel wheel 11 arranged concentrically with the bolt 4 and carrying an outer toothed rim 12. This toothed rim is in engagement with the toothed wheel 13 secured to the running wheel or roller 3. The spindle 9 is surrounded, on

the section from the oil tank to the suspension head, by a tube 14, which is so wide that an annular space is left between the spindle and the tube for conveying the oil upward. 60 The said annular chamber is adjoined at the top in the suspension head by a bore 15 which goes into the bolt 4, is carried in the latter along a certain length and then terminated direct above the bearing cable 17. 65 The chamber 18 of the oil tank, in which is mounted the pump 8, is connected by means of an overflow pipe 19 to the other portion of the oil tank. A valve 20 enables the cross-section of the overflow to be modified, and 70 in that way, the quantity of the oil which is forced upward in the tube 14, to be regulated. This regulation could of course also be effected by other auxiliary means.

The device is not limited to the use of a 75 rotary pump but can be worked by means of any desired kind of pump. The essential point for obtaining the object of the invention is merely the arrangement of the driving spindle, and the transmission of motion 80 from the running wheel to the said driving spindle.

Having fully described my invention, what I claim and desire to secure by Letters Patent is:—

1. In a cable lubricator, the combination of, a running gear frame; rollers therein; a bolt on the frame; a suspension on said bolt; a tank and a pump therefor on said suspension; a spindle connecting with the pump 90 and passing through said bolt; a gear wheel on said spindle; and a gear co-axial with said bolt and adapted to transmit motion from one of said rollers to said gear wheel.

2. In a cable lubricator, the combination 95 of, a running gear frame; rollers therein; a bolt passing through the frame; a suspension on said bolt; a tank on the suspension; a pump communicating with the tank; a spindle connected to the pump and passing 100 through said bolt; a gear wheel on said spindle; and a gear co-axial with said bolt and adapted to transmit motion from one of the rollers to said gear wheel.

3. In a cable lubricator, the combination 105 of, a running gear frame; rollers therein; a bolt passing transversely through the frame and provided with an oil conveying bore; a wheel on said bolt and adapted to be rotated by one of the rollers; a suspension carried 110 on the bolt; a tank thereon; a pump communicating with the tank; an operative con-

nection between the pump and said wheel; and means for establishing communication between the pump and said bore.

4. In a cable lubricator, the combination of, a running gear frame; rollers therein; a bolt passing through the frame and projecting at one side of the frame and provided with an oil conveying bore; a gear wheel on said bolt and adapted to be rotated by one of said rollers; a suspension carried on the projecting part of said bolt; a tank on the suspension; a pump in the tank; a spindle connected to the pump; a bevel wheel on the spindle and engaging said gear; and means establishing communication between said pump and said bore.

5. In a cable lubricator, the combination of, a running gear frame; rollers therein; a toothed wheel on one of the rollers; a bolt 20 passing transversely through the frame and projecting at one side thereof and provided with an oil conveying bore; a suspension hanging from the projecting end of said bolt; a bevel gear on said bolt and engaging said toothed wheel; a tank on said suspension; a pump in said tank; a tube connecting the pump to said bore; a spindle operatively connected to the pump; and a bevel wheel on said spindle and engaging said bevel gear.

30 6. In a cable lubricator, the combination of, a running gear frame; rollers therein; a toothed wheel on one of the rollers; a transverse center bolt passed through the frame and projecting at one side of the frame and

provided with a longitudinal oil conveying 35 bore; a suspension hanging on the projecting part of said bolt; a bevel gear on said bolt and having a toothed rim engaging said toothed wheel; a tank on the suspension; a pump in the tank; a tube connecting the 40 pump to said bore; a spindle operatively connected to the pump and passing through the tube and said bolt; and a bevel wheel on said spindle and engaging said bevel gear.

7. In a cable lubricator, the combination 45 of, a running gear frame; running rollers secured thereto; a toothed wheel on one of said rollers; a bolt passed transversely through the frame and projecting at one side of the frame, and provided with an oil-conveying bore; a suspension swing on the projecting part of said bolt; a bevel gear on said bolt and provided with a toothed rim 50 engaging said toothed wheel; an oil box on the suspension; an oil chamber therein; a pump in said chamber; a tube leading from said pump to said oil conveying bore; a spindle operatively connected with the pump and extending through said pipe to a point above said bolt; and a bevel wheel on 55 said spindle and engaging said bevel gear.

In testimony whereof, I have signed my name to this specification in the presence of two subscribing witnesses.

OTTO LÖWENBERG.
